DESIGN FOR A BOILER

William C. Coleman, Wichita, Kans.

Application September 8, 1934, Serial No. 53,240

Term of patent 7 years

To all whom it may concern:

Be it known that I, Wm. C. Coleman, a citizen of the United States of America, residing at Wichita, in the county of Sedgwick and State of Kansas, have invented a new, original, and ornamental Design for Boilers, of which the following is the specification, reference being had to the accompanying drawing, forming a part thereof.

Figure 1 is a front view of boiler showing my design.

Figure 2 is a side view of the same.

I claim:

The ornamental design for a boiler as shown. In testimony thereof, I affix my signature.

WILLIAM C. COLEMAN.
